Joseph Arthur Gottlieb, Los Angeles, Calif.

Application April 30, 1936, Serial No. 77,255

4 Claims. (Cl. 120—34)

This invention relates to improvements in line indicating devices and has particular reference to a device upon which written or printed matter may be supported in such a manner that a marker 5 will move thereover in a step by step manner.

A further object is to produce a device of this character which is economical to manufacture, easy to operate, and portable.

Other objects and advantages will be apparent 10 during the course of the following description.

In the accompanying drawings forming a part 15 of this specification and in which like numerals are employed to designate like parts throughout the same,

15 Fig. 1 is a side elevation of my device having a portion thereof broken away;

Fig. 2 is an enlarged fragmentary detailed view 20 of the ratchet mechanism;

Fig. 3 is a front elevation of Fig. 1;

25 Fig. 4 is a side elevation of my device folded;

Fig. 5 is an enlarged fragmentary detailed view 30 of the sheet holding clamp; and

Fig. 6 is a perspective view of the book holding 35 support.

25 In copying matter, such as, typewriting, shorthand, or other indicia from books, loose sheets, or notebooks, it is customary for the copyist to place the material at one side of the typewriter, with the result that the head must be constantly 40 turned in looking at the material and then at the matter copied upon the typewriter sheets.

I have, therefore, devised a mechanism which 45 may be placed behind the typewriter upon which the material to be copied is supported, and I have arranged an indicator for moving over the material a step at a time. This places the material to be copied in direct line with the copyist's eyes and also in alignment with the typewriter sheets. Consequently, it is only necessary to 50 shift the eyes a short distance in order to observe both the matter being copied and the impressions upon the sheets.

In the accompanying drawings wherein for the 45 purpose of illustration is shown a preferred embodiment of my invention, the numeral 5 designates a base plate having upstanding standards 6 and 7 upon which is slidably supported the bottom section 8, and any well-known means 50 may be used for clamping this bottom section to the uprights and in adjusted position. Hinged to the bottom section is a top section 9, the 55 hinges being located at 11, and springs 12, offset from the hinges 11, maintain the upper and lower sections either in the position of Fig. 1 or in the position of Fig. 4. Carried upon the upper

end of the top section is an offset sheet holding rod 13 actuated by a handle 14 and having its offset portion held against the sheet by a spring 16. A sheet holding clamp 17 is also carried upon the upper section 9 and is normally held by a 5 spring 18 in the full line position of Fig. 5.

In order to hold books other than notebooks, I employ a hanger 19 (see Fig. 6). The position this hanger assumes when in use is shown in full lines in Fig. 3. The numeral 21 designates 10 an indicator carried upon the block 22, which block is pivoted through parallel arms 23 to a slider 24. A spring 26 tends to keep the marker and its block in the full line position of Fig. 1; or if moved to the dotted line position of this 15 figure, the spring tends to keep the marker against matter being copied, irrespective of its thickness. The slider 24 travels in a track 27 and has a cable 28 connected to one end thereof, which cable passes downwardly through the track under a 20 pulley 29, thence over a driving pulley 31, thence under a pulley 32 and has its free end connected to a tension spring 33. A similar cable 34 is connected to the opposite end of the tension spring and passes upwardly over a pulley 36 and has its 25 free end connected to the upper end of the slider 24. This arrangement is such that when the driving wheel 31 is revolved in the direction of the arrow of Fig. 1, the slider will be moved downwardly in its track, and in order to rotate the 30 driving pulley 31, I employ a ratchet 37 which is engaged by a dog 38 carried upon a lever 39. This lever is pivoted as at 41 and has its end 42 connected by a spring 43 to a supporting member 44. This supporting member 44 is slidable on a pivoted 35 brace 46, hinged as at 47 to the base 5. A stop 48 is slidable upon the lever 39 and may be moved into engagement with either the abutment 49 or 51. These abutments determine whether the driving wheel 31 moves a distance sufficient to 40 move the indicator one or two spaces. A hand wheel 52 enables the user to return the indicator upwardly in a rapid manner, the dog 38 only engaging the teeth of the ratchet on the downward movement of the lever 39. When the device 45 is folded, as shown in Fig. 4, the same takes up a relatively small space and may be easily transported from place to place.

It will thus be seen that I have produced a device which will accommodate sheets, papers, 50 notebooks, or thick-bound volumes with equal facility.

It is to be understood that the form of my invention herewith shown and described is to be taken as a preferred example of the same and 55

that various changes relative to the material, size, shape and arrangement of parts may be resorted to without departing from the spirit of the invention or the scope of the subjoined claims.

5 Having thus described my invention, I claim:—

1. In a copy holder having a bottom section and a top section hingedly carried by the bottom section, of means remote to said sections for moving an indicator over said sections, said means including a cable connected to said indicator, and a lever actuated driving pulley for moving said cable in a step by step manner.
2. In a copy holder having a bottom section and a top section hingedly carried by the bottom section, of means remote to said sections for moving an indicator over said sections, said means including a cable connected to said indicator, a lever actuated driving pulley for moving said cable in a step by step manner, said indicator being adjustably supported whereby said indicator may be moved away from the section over which it is travelling and held parallel thereto.

3. In a copy holder having a pair of hinged sections, of a track mounted on each of said sections, a slider movable in said tracks, an indicator movably supported on said slider, and remotely operated means for moving said slider and said indicator in a step by step manner.

4. In a copy holder having a pair of hinged sections, of a track mounted on each of said sections, a slider movable in said tracks, an indicator movably supported on said slider, remotely operated means for moving said slider and said indicator in a step by step manner, said remotely operated means including a cable extending through said tracks, one end of the cable being connected to each end of said slider, pulleys positioned at each end of said track over which said cable passes, and a ratchet operated pulley over which said cable is reeved, whereby actuation of said last-mentioned pulley moves said marker over said sections.

JOSEPH ARTHUR GOTTLIEB.
